CLAIM

I claim the ornamental design for a housing of an extrusion press, as shown and described.

DESCRIPTION

FIG. 1 is a front perspective view of a housing of an extrusion press embodying my design;

FIG. 2 is a right side elevational view of FIG. 1;

FIG. 3 is a left side elevational view of FIG. 1;

FIG. 4 is a front elevational view of FIG. 1;

FIG. 5 is a back elevational view of FIG. 1;

FIG. 6 is a top plan view of FIG. 1; and,

FIG. 7 is a bottom view of FIG. 1.

1 Claim, 4 Drawing Sheets

FIG. 1
